United States Patent Office

Des. 196,394
Patented Sept. 24, 1963

196,394

CONTAINER FOR DAIRY PRODUCTS OR THE LIKE

Clara Virginia Eicholtz, Midland, Mich., assignor to The Dow Chemical Company, Midland, Mich., a corporation of Delaware

Continuation of design application Ser. No. 65,818, July 6, 1961. This application July 25, 1962, Ser. No. 71,040

Term of patent 14 years

(Cl. D58—17)

Fig. 1

Fig. 2

FIGURE 1 is an elevational view of a container for dairy products or the like, showing my new design;

The dominant features of my design reside in the portions shown in full lines.

This is a continuing application of application Serial Number D. 65,818, filed July 6, 1961, now abandoned.

I claim:

The ornamental design for a container for dairy products or the like, as shown and described.
